UNITED STATES PATENT OFFICE.

JOHN T. WESTWOOD, OF WHEELING, WEST VIRGINIA, ASSIGNOR OF ONE-THIRD TO BENJAMIN FISHER, OF SAME PLACE.

CAR-SEAT.

SPECIFICATION forming part of Letters Patent No. 409,654, dated August 20, 1889.

Application filed May 7, 1889. Serial No. 309,917. (No model.)

To all whom it may concern:

Be it known that I, JOHN T. WESTWOOD, a citizen of the United States, residing at Wheeling, in the county of Ohio and State of 5 West Virginia, have invented new and useful Improvements in Car-Seats; and I do hereby declare the following to be a full, clear, and exact description of said invention, reference being had to the accompanying drawings, and 10 to the letters or figures of reference marked thereon, which form a part of this specification.

My invention relates to improvements in car chairs or seats; and the object of my invention is to provide a seat which will at all 15 times be supported in a vertical position and at the same time relieve the occupant of the car of the annoying and painful sensation produced by the lateral motion of the car.

20 My invention consists in supporting the seat of a railway-car in such a manner that it will always remain in a vertical position with relation to the car-floor, and in providing each side of the seat with foot-rests, whereby the 25 occupant of the chair will be practically isolated from the floor of the car and be unaffected by the motion of the same.

Figure 1 is a view in perspective of a car-seat supported by my devices. Fig. 2 is a 30 sectional view of one of the supports. Fig. 3 is a front view of the two-part hanger used for inclosing the balls forming the bearings. Fig. 4 is an end view of the seat, showing foot-rests on each side. Fig. 5 is a detached perspective view of the foot-rest.

35 A indicates the ordinary seat of a railway-car having a reversible back, but may be a chair or other approved form of seat.

B indicates the car-floor or other base to 40 which the supports C are firmly secured. The supports C are horn-shaped, having a wide base, and are provided at their upper ends with balls a for engaging the upper ends of the hangers D. For the support of an ordinary car-seat I employ four of these standards, with their corresponding hangers; but a greater or less number may be employed without departing from the spirit of my invention. The hangers D are made in two parts, as 45 shown in Fig. 3, with hemispherical concaved recesses b at each end for receiving the balls a

of the standards, thus making a ball-and-socket joint, when the two parts of the hanger are put together and secured by means of screws or other suitable fastening devices. 55

E E' are two sets of curved or horn-shaped arms, the upper ends of one set E being firmly secured to the under side of one end frame of the car, about flush with the bottom, while the upper or outer ends of the other set E' 60 are similarly secured to the lower ends of downward extensions or legs of the other end frame of the car-seat, said latter set of arms being preferably reduced or flattened and shouldered, as shown, for the convenient application of the same to the said end-frame extensions or legs. The lower ends of said arms are provided with balls F, which engage the spherical sockets formed on the lower ends of the hangers D. 70

G are bars or rods secured to the under side of the seat and at both sides thereof, near the ends of the same, the free ends of said bars being projected downward to within a short distance of the car-floor. 75

H is a board, metal plate, or metal grating, pivoted at each end between the lower ends of the bars or rods G, said boards or plates forming foot-rests on both sides of the seats, so that when the seats are reversed to correspond to the direction of the train a foot-rest 80 will be ready for use.

The ends of the foot-rests are provided with angle-irons I, which have an outwardly-projecting lug or bend K at their rear ends, 85 adapted to abut against the rear edges of the bars G and thus form a reliable stop for the foot-rest and hold the same securely in position. When it is not desirable to have the foot-rest in use, it is turned up out of the way, 90 as shown in rear of seat in Fig. 4.

It will be apparent from the above description that by the use of the devices mentioned I am enabled to support the seat, chair, or other like article, so that it will always remain in a vertical position, and when the occupant has his feet upon the rest H he will be isolated from the floor, and will be oblivious to the lateral choppy motion of the car as well as to the longitudinal concussions incident 100 to the quick application of the brakes or jars incident to the coupling of the cars.

It will be understood that I do not restrict myself to details of construction, as it is obvious that changes may be readily made therein without departing from the spirit of my invention.

Having thus described my invention, what I claim is—

1. A railway-car seat or chair consisting of standards secured to the floor, arms connected to the seat or chair, hangers connected to said standards and arms, and the bearing or supporting points formed of ball-and-socket joints, whereby the seat is adapted to always maintain a vertical position with relation to the car-floor, substantially as set forth.
- 15 2. A support for car-seats, chairs, &c., consisting of a series of horn-shaped standards having balls at their upper ends, the hangers

provided with sockets at their ends, and curved arms secured to the under side of the seat and having balls at their lower ends, the balls of the standards and arms engaging the sockets in the ends of the hangers, substantially as set forth.

3. A car-seat consisting of arms pendent from the seat, standards secured to the floor, hangers having ball-and-socket joint connections with said arms and standards, and elevated foot-rests on each side of the seat, substantially as set forth.

In testimony whereof I affix my signature in the presence of two subscribing witnesses.

JOHN T. WESTWOOD.
